UNITED STATES PATENT OFFICE

WILLIAM D. BERRY, OF NEW BRIGHTON, PENNSYLVANIA.

APPARATUS FOR MAKING SAND CORES.

No. 887,758.

Specification of Letters Patent.

Patented May 19, 1908.

Application filed June 12, 1907. Serial No. 378,634.

To all whom it may concern:

Be it known that I, WILLIAM D. BERRY, a resident of New Brighton, in the county of Beaver and State of Pennsylvania, have invented a new and useful Improvement in Apparatus for Making Sand Cores; and I do hereby declare the following to be a full, clear, and exact description thereof.

This invention relates to apparatus for making sand cores, and more especially to the making of green sand cores to be used in the casting of tubular articles.

The object of the invention is to provide apparatus for this purpose adapted especially for making these cores by a jarring operation so as to dispense largely with the hand work generally employed for making such cores, to improve uniformity of packing and also to expedite the manufacture so as to cheapen the making of such cores.

The invention comprises the construction of parts hereinafter described and claimed.

In the accompanying drawings Figure 1 is a central vertical section through the apparatus showing a portion of the jarring machine for forming the core; Fig. 2 is a central vertical section through the finished core and showing the manner of handling the same; and Figs. 3, 4 and 5 are detail sectional views of the core box, the core pan, and the centering ring respectively.

In carrying out my invention I can use any form of jarring mechanism and in the drawings only a portion of one form of mechanism has been shown. This comprises a suitable frame 1 on which is mounted for vertical movement the machine plate 2. This may be elevated, then dropped and suddenly stopped by any suitable means, such as providing an air cylinder 3 to lift the same and permit the same to drop and strike an anvil 4. Any other means may, however, be employed for jarring the plate 2.

The plate 2 is provided on its upper face with a central circular depression 6 and centrally of this with a hole 7 preferably tapped, as shown, to receive a bolt for securing other parts of molding apparatus to said machine plate. Fitting in the central depression 6 of the machine plate is a centering plate 9 which forms the bottom plate of the mold. This bottom plate is provided centrally with an opening surrounded by an upwardly projecting wall or flange 10, said opening having practically perpendicular walls 11 at the top while below the same the walls may taper in-

wardly. Adapted to seat in this opening in the bottom plate is a metallic core pan 13 having edge portions 14 which fit closely against the walls of the opening in the bottom plate but do not extend up to the top of the wall or flange 10. At its center the core pan is provided with a thickened portion or boss 15 which is provided with a threaded socket for receiving the lower end of a pipe 16 which is provided with perforations 17 and serves as a vent for the escape of the gases during casting. This perforated pipe at its upper end has secured to it an internally threaded socket 18 to receive during the jarring operation a suitable closure, such as a plug 19 to prevent the entrance of sand into said pipe, and also serving as a convenient means for the attachment of a handle 20, as shown in Fig. 2, for carrying and otherwise handling the core.

The core box 21 at its lower end is provided with a flange 22 resting on the flange or wall 10 of the bottom plate and having a down-turned lip 23 passing down outside of said wall and serving to center the core box on the bottom plate. This core box will be made interiorly of the shape of the desired core, being shown as tapering toward the top, and at its base it projects inwardly beyond the inner face of the wall 10, as shown at 24, so as to leave between the same and the top of the edge 14 of the core pan a space 25 into which the sand will fill in order to provide a covering of sand above the edge of the core pan and prevent the hot metal in casting coming against said core pan. The core box may be of a single piece or formed in sections as shown.

In conjunction with this apparatus and for jarring purposes I provide a reservoir 27 of any desired construction.

In the use of the apparatus described the centering or mold bottom plate 9 is placed in the depression 6 in the machine plate. A core pan 13 with its perforated tube is then placed in the opening in the mold bottom plate and the top of the vent pipe 16 is closed by means of a plug 19. The mold box 21 is then set down on to the flange of the mold bottom plate and the reservoir 27 placed on top of the core box. Sand is then filled down into the reservoir, either by hand or suitable machine, and the machine set in operation to jar the sand down into the mold in the usual way.

When sufficiently jarred the sand is cut

off at the top of the core box and the reservoir removed or the mold moved from under the reservoir. The plug 19 is then removed and a handle 20 is screwed down into the 5 socket 18. The core box is then removed and the molded core lifted out of the machine by means of the handle 20, said core being supported by the core pan 13. The core pan and perforated tube remain with the core 10 during casting and will then be used in the making of further cores. The core can be baked if desired or used green. The other mold parts will be so shaped as to bring the parting at the upper edge of the flange 26 15 which is formed on the core above the top edge of the core pan so that in casting the hot metal can not touch the pan.

The apparatus described is of simple construction, can be adapted to any jarring machine and provides for the making of cores expeditiously and with a minimum amount of labor. Many modifications are, of course, possible, without affecting the principle of the invention.

25. What I claim is:—

1. Core molding apparatus comprising a bottom plate provided with an opening, a core pan seating in said opening, and a core box open at its top and bottom and seating 30 on the bottom plate concentric with said opening.

2. Core molding apparatus comprising a bottom plate provided with an opening surrounded by a flange or wall, a core pan seating in said opening, and a core box open at top and bottom and seating on the flange 35 surrounding the opening in the bottom plate.

3. Sand molding apparatus comprising a bottom plate provided with an opening surrounded by a flange or wall, a core pan seating in the opening in said plate with its edge portions below the top of the flange or wall thereon, and a core box open at the top and bottom and seating on the flange or wall on 40 the bottom plate and overhanging the edge of the pan to leave a space between itself and the top edge of the pan.

4. Core molding apparatus comprising a bottom plate provided with an opening sur-

rounded by a flange or wall, a core pan having tapering edge portions fitting into said opening, and a core box open at top and bottom and seating on the flange or wall of the bottom plate. 50

5. Core molding apparatus comprising a bottom plate provided with an opening, a core pan seated in said opening, a column secured to said core pan and having means at its upper end for the attachment of a handle, and a core box seating on said bottom plate. 60

6. Core molding apparatus comprising a bottom plate provided with a central cavity, a core pan seating in said cavity, a column secured to said core pan, and a threaded member on the upper end of the column for 65 the attachment of a handle.

7. Core molding apparatus comprising a bottom plate provided with a central cavity, a core pan seating in said cavity, a tubular column rising from said core pan, a threaded 70 socket at the upper end of said column, and a core box seating on said bottom plate.

8. Core molding apparatus comprising a bottom plate provided with a central cavity, a core pan seating in said cavity, a perforated 75 tube secured to said core pan and having internal threads at its upper end, and a core box seating on said bottom plate.

9. Core molding apparatus comprising a bottom plate provided with a central cavity, 80 and a core pan seating in said cavity, a perforated pipe secured to said core pan and provided at its upper end with means for the attachment of a handle.

10. Core molding apparatus comprising in 85 combination a machine plate provided with a central depression, a mold bottom plate fitting in said depression and provided with an opening, a core pan seating in said opening, and a core box open at top and bottom 90 and fitting on the bottom plate at the edge of said opening.

In testimony whereof, I the said WILLIAM D. BERRY, have hereunto set my hand.

WILLIAM D. BERRY.
